UNITED STATES PATENT OFFICE.

ERASTUS L. CLEVELAND, OF WEST CHICAGO, ILLINOIS.

DRILL-JAR.

1,144,814.

Specification of Letters Patent. Patented June 29, 1915.

Application filed February 17, 1915. Serial No. 8,796.

To all whom it may concern:

Be it known that I, ERASTUS L. CLEVELAND, a citizen of the United States, residing at West Chicago, in the county of DuPage and State of Illinois, have invented in certain new and useful Improvements in Drill-Jars, of which the following is a specification.

This invention relates to devices for connecting a well-drilling tool to the drill-rope in such a manner that the tool is jarred during the drilling operation.

The object of the present invention is to provide a novel and improved drill jar and rope socket combined, which is highly efficient in operation and simple in construction, this object being attained by means of a combination and arrangement of parts to be hereinafter described and claimed, reference being had to the accompanying drawings forming a part of this specification.

In the drawing, Figure 1 is an elevation of the device, and Fig. 2 is a central vertical section thereof.

Referring specifically to the drawing, 5 denotes a stem having at its lower end a longitudinal cavity 6 in which works a jarring head 7 carried by a wire rope 8. The stem has a central longitudinal passage 9 extending from its upper end and opening into the cavity 6, through which passage the rope loosely extends. The lower end of the cavity is threaded, as indicated at 10, for attachment of the drill or other tool, the latter being thus carried by the stem 5.

The stem 5 is not directly connected to the drill-rope 11, a socket member 12 being provided to which said rope is connected, and said member carrying the suspension rope 8 of the stem 5. This socket member has a longitudinal passageway 13 which opens at its lower end into a cavity 14 in the lower end of the member, in which cavity the upper end of the stem 5 is slidably mounted. Where the passageway 13 opens into the cavity 14, it is reduced to form an inverted conical cavity 15 in which the upper end of the rope 8 is made fast by being spread thereinto and soldered or babbittted, the solder or Babbitt metal being poured in

through a duct 16 extending laterally from the cavity and opening through the side of the member 12. The passage 13, intermediate its ends, has a lateral branch in which the rope 11 is made fast in the ordinary manner.

It will be evident from the foregoing that a loose connection between the stem 5 and the drill rope 11 is provided, so that when the latter is operated the head 7 and the opposite inner wall of the cavity 6 strike and then separate, whereby the drill or other tool carried by the stem is jarred. The stem is guided by the cavity 14 in the socket member 12, and the length of the rope 8 is such as to give the stem sufficient travel to produce an effective jar. The structure also enables a heavy rope 11 to be used and a lighter rope 8 for the suspension of the stem 5.

I claim:

1. The combination of a well-drilling tool-stem having a cavity, a jarring head in the cavity, a suspension means connected to the jarring head, and a drill-rope socket member having a bottom cavity in which the upper end of the tool stem is slidably mounted, to which member the aforesaid suspension means is connected.

2. The combination of a well-drilling tool-stem having a cavity, a jarring head in the cavity, a drill-rope socket member having a bottom cavity in which the upper end of the tool-stem is slidably mounted, and a connection between the socket member and the jarring head.

3. The combination of a well-drilling tool-stem having a cavity, a jarring head in the cavity, a drill-rope socket member having a bottom cavity in which the upper end of the tool-stem is slidably mounted, and a suspension rope carrying the jarring member and connected to the socket member at the upper end of its cavity.

In testimony whereof I affix my signature in presence of two witnesses.

ERASTUS L. CLEVELAND.
